US0D1005369S

(12) **United States Design Patent** (10) **Patent No.:** **US D1,005,369 S**
(45) **Date of Patent:** **** Nov. 21, 2023**

(54) **SECURITY MONITORING DEVICE MOUNT**

(71) Applicant: **Canary Connect, Inc.**, New York, NY (US)

(72) Inventors: **Matthew Rao**, Massapequa Park, NY (US); **James C. Krause**, Astoria, NY (US); **Johan Liden**, New York, NY (US); **Brett Tom**, San Francisco, CA (US); **Eric Joseph Call**, New York, NY (US)

(73) Assignee: **Canary Connect, Inc.**, New York, NY (US)

(**) Term: **15 Years**

(21) Appl. No.: **29/734,993**

(22) Filed: **May 18, 2020**

Related U.S. Application Data

(62) Division of application No. 29/668,685, filed on Nov. 1, 2018, now Pat. No. Des. 888,138, which is a division of application No. 29/572,257, filed on Jul. 26, 2016, now Pat. No. Des. 836,147.

(57) **CLAIM**

The ornamental design for a security monitoring device mount, as shown and described.

DESCRIPTION

FIG. 1 is a front, right perspective view of a security monitoring device mount showing our new design;

FIG. 2 is a rear, left perspective view thereof;

FIG. 3 is a top view thereof;

FIG. 4 is a front view thereof;

FIG. 5 is a right view thereof;

FIG. 6 is a left view thereof;

FIG. 7 is a rear view thereof; and,

FIG. 8 is a bottom view thereof.

The broken lines shown in the drawings are for the purpose of illustrating portions of the security monitoring device mount that form no part of the claimed design.

1 Claim, 4 Drawing Sheets
